UNITED STATES PATENT OFFICE.

WILLIAM M. CARY, OF HOLYOKE, MASSACHUSETTS.

ENVELOP.

1,117,479.

Specification of Letters Patent. Patented Nov. 17, 1914.

Application filed June 17, 1914. Serial No. 845,697.

To all whom it may concern:

Be it known that I, WILLIAM M. CARY, a citizen of the United States, residing at Holyoke, in the county of Hampden and 5 State of Massachusetts, have invented certain new and useful Improvements in Envelops, of which the following is a specification, reference being had to the accompanying drawings.

10 This invention relates to improvements in envelopes, and has for its primary object to provide an article of this character which is so constructed as to securely retain the contents thereof against probable loss in transit, but which can be readily opened and 15 the contents removed without mutilating the envelop to such an extent as to preclude its subsequent use.

Broadly considered, the present invention 20 contemplates the provision of an exterior pocket upon the back or rear side of the envelop at its open end, and a closure flap provided with an extension tongue adapted to be folded and inserted into said pocket to 25 retain the flap in its closed position.

In its more specific aspect, the invention 30 provides an envelop constructed from a paper blank cut by means of a suitable die to produce side flaps on opposite edges of the body portion, end flaps constituting continuations of said body portion and a tongue 35 on one of said end flaps, said side flaps being provided with extensions on one of their ends projecting beyond the body of the envelop, said flaps and the extensions being 40 folded relative to each other and with respect to the body of the envelop to produce the rear envelop wall and a pocket at the upper edge thereof, the end flap provided with the tongue being adapted to be folded 45 over the upper edge of said rear wall and the tongue reversely folded and introduced into said pocket.

The invention has for a further general 50 object to provide an envelop which is extremely simple in its construction, may be manufactured at small cost, and is very durable, as well as highly serviceable and convenient in practical use.

With the above and other objects in view,

the invention consists in novel features of construction, combination, and arrangement of parts as will be hereinafter referred to and more particularly pointed out in the specification and claim.

55

For a full understanding of the invention, reference is to be had to the following description and accompanying drawing, in which—

Figure 1 is a plan view of the blank sheet 60 from which the envelop is formed; Fig. 2 is a rear face view showing the several flaps as they fold by machine to produce a pocket at the open end of the envelop; Figs. 3, 4, 5 and 6 are detail sectional perspective 65 views illustrating the several steps in the folding and closing of the envelop; and Figs. 7 and 8 are fragmentary elevations illustrating alternative forms of the invention.

70

Referring in detail to Figs. 1 to 6 inclusive of the drawing, A designates the blank from which the envelop is constructed. This blank is cut from a paper sheet of the desired texture and includes a 75 main body portion 1, side flaps 2 and 3 at the opposite edges of said body portion, a bottom flap 4 at one end of said body portion and the closure flap 5 at the opposite end thereof. The flaps 2 and 3 are each 80 provided with an extension 6 on one end projecting beyond the end of the body 1 for substantially the same distance as the flap 5. The closure flap 5 may be of various forms, but, as illustrated, the end edges 85 7 thereof at their junction with the body of the envelop are slightly spaced from the opposed edges of the extensions 6 on the side flaps 2 and 3, said opposed edges of the closure flap and the extensions 6 being equidistantly spaced from the lines upon which the side flaps 2 and 3 are folded, said lines being designated by the numeral 8. The side flap 3 is of slightly greater width than the flap 2 and the marginal edge of said 90 flap 3 is adapted to lap over slightly upon the corresponding edge of the flap 2 when said flaps are folded over upon the body 1 of the blank. This marginal edge of the flap 3 is gummed throughout its length, as 10

indicated at 11. The opposite or outer faces of the extensions 6 of the flaps 2 and 3 are also gummed along their inner edges as indicated at 11' for a purpose which will later appear.

The closure flap 5 on one end of the body 1 of the blank is formed with a reduced tongue or extension 10. By now referring to Fig. 2 of the drawing, the manner in which the envelop is produced will be apparent. The flaps 2, 3, and 4 and the extensions 6 are folded by a suitable machine. The flap 2 is first folded along the line 8 inwardly upon the body 1 and the other side flap then similarly folded and adhesively secured along its marginal edge upon the edge of the flap 2. The bottom flap 4 is then folded over upon the lower ends of the flaps 2 and 3 and also adhesively secured thereto. The extension 6 of the flaps 2 and 3 are now folded downwardly upon said flaps and the gummed end edges 11' of said extensions adhesively secured to the respective flaps. Thus it will be clearly apparent that a pocket is formed between these folded extensions and the opposed upper end portions of the flaps 2 and 3. In this condition the envelop is delivered from the folding machine. The user after inserting the letter or other mailable matter into the envelop between the body 1 and the flaps 2 and 3, folds the closure flap 5 over the open end of the envelop and upon the extensions 6 of the flaps 2 and 3 which constitute the back wall of the envelop. The tongue 10 is now folded along the line 10' and forced upwardly under the extension 6 between the same and the rear wall of the envelop. Thus, the closure flap 5 will be securely held in its closed position by confining the extension or tongue 10 thereof within said pocket. This completely closed condition of the envelop is clearly illustrated in Fig. 6 of the drawing.

In Fig. 7 of the drawing I have illustrated a slightly different form of the device, wherein the extension 6^a of the side flap 3 is not only gummed on its inner end edge as shown at 13, in a manner corresponding to the preferred form of the invention above described, but the extension upon the flap 3 is also gummed upon its outer edge as indicated at 12. Thus, it will be seen that when these extensions are folded down upon the flaps, the moistened gummed edges 12 and 13 will adhere to said flaps and produce spaced pockets instead of a single tongue receiving pocket. The closure flap 15 is this form of the invention is therefore cut to provide tongues 14 for engagement in the respective pockets.

In Fig. 8 of the drawing, I have illustrated still another envelop construction, wherein the blank is cut to provide the body portion 16 and narrow side flap 17 and a

wide side flap 18. The marginal edge of this latter flap is gummed so that the same will adhere to the flap 17 upon which it is adapted to be folded. The wider flap 18 is provided upon its upper edge with an extension 21, which is gummed upon its end edges so that when the same is folded upon the flap 18, the tongue receiving pocket is produced to accommodate the tongue on the closure flap 20. A bottom flap is, of course, formed on the lower end of the envelop body in the same manner as shown in Fig. 1 of the drawing.

From the foregoing description taken in connection with the accompanying drawing, it is believed that the construction, and several advantages of my improved envelop will be clearly and fully understood. The locking tongue on the closure flap when inserted into the pocket formed by the folded extensions 6 operates to effectually retain said closure flap in its folded or closed position over the open end of the envelop. This locking tongue being thus closely confined, will not work out of the pocket by shifting movement or agitation of the envelop during transit, while at the same time the addressee may easily and quickly obtain access to the contents of the envelop by simply inserting a knife or other implement into the pocket and pulling the tongue 10 therefrom. The envelop need not therefore be destroyed or so mutilated as to preclude its subsequent use as a container or protecting envelop for papers or other articles.

It will thus be appreciated that I have produced a very simple and inexpensive as well as highly serviceable envelop or container wherein the use of metallic fasteners is entirely dispensed with and one which may be very easily and quickly opened or closed. It will, of course, be obvious that the envelop may be constructed of paper of various grades or texture as well as of linen or other desired material.

What is claimed is:

An envelop constructed from a blank having a body wall to constitute the front of the envelop and side flaps on the opposite edges of said body wall, one of said side flaps being provided with an extension on one of its ends, the longitudinal edge of said flap and the corresponding edge of said extension being gummed upon one face to adhere to the other side flap, when said flaps are folded over upon the body of the envelop, said extension of said side flap being also gummed upon its other face and on the opposite edge thereof with respect to the first referred to gummed edge, whereby said extension when folded outwardly upon the side flap will permanently adhere thereto and form a pocket upon one end of said flap, and a closure flap on the corresponding

end of the body wall of the envelop provided with a reduced tongue, said flap being adapted to be folded over upon the extension of the side flap and the tongue thereof 5 reversely bent and introduced into said pocket to retain the closure flap over the open end of the envelop.

In testimony whereof I hereunto affix my signature in the presence of two witnesses.

WILLIAM M. CARY.
